SOUND RECORDING

Application filed October 30, 1929. Serial No. 403,492.

This invention relates to sound recording and reproducing systems and particularly to those capable of embracing a range of frequencies in excess of the present high quality range.

It is the object of the invention to provide means for utilizing a single groove as a record of variations in two or more frequency bands.

10 Prior to this invention it has been proposed as in Affel Patent 1,595,135, granted Aug. 10, 1926 to split a band of speech frequencies into a number of sub-bands for separate transmission over circuits each of which, due 15 to inherent limitations, is incapable of transmitting the whole band. Suitable means is then provided at the receiving point to reassemble the components into the original band. Also in Lindridge Patent 1,675,894, granted 20 July 3, 1928 it was proposed to apply this general idea to a recording system in which the record material had inherent limitations analogous to those of Affel's transmission circuits.

25 In my copending application Serial No. 402,128, filed Oct. 24, 1929, there is disclosed a sound reproducer capable of responding to a range of frequencies much in excess of the present commercial high quality band which 30 may be said to extend up to about 4500 cycles. The necessary design formula and general instructions are given in that application for designing a reproducer capable of responding to the complete audible range and also to 35 higher frequencies. It is also now possible to design recorders capable of making a satisfactory record of frequencies much in excess of the commercial range mentioned above.

In accordance with the present invention, 40 therefore, it is proposed by the use of such novel recorders and reproducers to make an entirely new form of record, namely, one in which the sounds from two or more separate sound sources, each embracing a range of frequencies sufficient for good quality sound reproduction, are recorded in the same record groove. According to the preferred method of carrying out the invention the frequencies representing the various extra record bands 45 are displaced in the frequency scale by modu-

lation to form a progressive series of bands separated by suitable intervals. This composite band is then recorded on a record blank of the proper physical characteristics for such a wide range of frequencies, and in the 55 reproducing circuit the bands are separated by filters and restored to their original position in the frequency scale for reconversion into sound through separate receiving means.

It will be understood, of course, that the 60 invention is not limited to making a unitary record of several similar frequency bands for it is also contemplated that it may be desirable to pick up and record vibrations above the ordinary audible range either separately or together with the usual sound frequencies. For instance the invention may be employed for simultaneously recording 65 for subsequent study and analysis the currents representing speech and those representing transient disturbances in telephone 70 circuits.

The following detailed description of one embodiment of this invention is given by way 75 of illustration but obviously many modifications within the scope of the invention will occur to those skilled in the art desiring to use such a recording and reproducing system for special purposes.

Fig. 1 of the drawing illustrates schematically the essential apparatus and connections for recording and reproducing a record according to the invention and Fig. 2 is a similar schematic of a recording system in which vibrations of different frequency ranges are 80 directly recorded.

In Fig. 1, 1, 2 and 3 are shown as conventional microphones but it should be understood that one or more of them may represent totally different sources of alternating currents as for instance a telephone line or other electric circuit. An amplifier 4 is provided at each source and the vibrations from microphone 1, which would ordinarily be 85 within the sound range of 60-4500 cycles, are further intensified by amplifier 5 and registered by recorder 6 on the record 7 which is rotated by turntable 12. The vibration source 2 may deliver a similar band of frequencies representing music or pressure va- 90 95 100

riations through its amplifier 4 to modulator 8 which by means of suitable carrier frequency supplied by oscillator 9 displaces the band to the 5060 to 9500 cycle range in the 5 well known manner.

Similarly, modulator 10 and oscillator 11 will shift the 60 to 4500 cycle currents from source 3 to the 10060 to 14500 cycle range and both these bands of higher frequencies will 10 also be recorded by recorder 7, superimposed upon the ordinary record.

In the reproducing system the original record 7 or a pressing 13 made from it is 15 rotated by turntable 14. Reproducer 15 is of a type such as that described in my co-pending application already mentioned, which is capable of responding to the highest frequency recorded and the currents generated by it are raised to a suitable level by 20 amplifier 16. Band pass filter 17 is of the low pass type so that only the frequencies recorded without modulation, in this case 60-4500 cycles will be passed to amplifier 18 associated with receiver 19. Filter 20 is 25 adapted to pass only the frequencies recorded in the 5060-9500 cycle range and this band by means of oscillator 21 and demodulator 22 is displaced to its original position in the 60-4500 cycle range for conversion 30 into sound through its receiver 23. Similarly, filter 24 selects the 10060-14500 cycle band and this is also shifted back to its original position and transmitted to receiver 25.

In Fig. 2 the devices 26 and 27 may be 35 microphones or any other sources of electrical variations of different frequency ranges, such as speech and superaudible variations, respectively, and as they are already separated by a sufficient frequency interval they 40 may be amplified and transmitted directly to the recorder 31 without modulation. In reproducing the record 32, however, it would be necessary to use suitable discriminating apparatus such as that shown in Fig. 1, for 45 separating the two bands.

What is claimed is:

1. In a recording system, a record blank and means for recording thereon in the same groove a high quality sound record and a 50 separable record of a band of frequencies extending above the range of the high quality sound record.

2. In a recording and reproducing system, a plurality of sources of frequency bands 55 each embracing the high quality sound range, means for transposing certain of the bands to produce a progressive series of bands separated by suitable frequency intervals and including the usual speech range, a record 60 blank and means for recording the series of bands on the record blank, unitary means for reproducing the series of bands, means for retransposing the bands to their original position in the frequency scale and receiving 65 means for each of the reproduced bands.

3. In a recording and reproducing system a plurality of sources of frequency bands each embracing the high quality sound range, means for increasing the amount of matter which may be recorded on a single record 70 blank comprising modulators for transposing certain of the bands to form a progressive series of bands separated by suitable frequency intervals, a record blank and means for recording the series of bands on the record blank, unitary means for reproducing the series of bands, band pass filters for separating the reproduced frequencies into the original number of bands, demodulators for 75 restoring the separated bands to their original frequency ranges, and receiving means for the restored bands.

4. In a recording and reproducing system a plurality of microphones each picking up frequency bands embracing the high quality sound range, vacuum tube amplifiers for each band, means for increasing the amount of matter which may be recorded on a single record blank comprising modulators for transposing said bands into a progressive 80 series of bands separated by suitable frequency intervals, a vacuum tube amplifier for the series of bands, a record blank and a recorder capable of recording the entire series of bands on the record blank, a reproducer for reproducing the recorded frequencies, a vacuum tube amplifier for strengthening the reproduced frequencies, band pass filters for separating the reproduced frequencies into the original number 85 of bands, demodulators for restoring the bands to their original frequency ranges, and receiving means for reproducing all of the 90 restored bands.

5. In a recording system a record blank 105 and means for recording thereon in the same groove frequencies representing sounds from at least two separate sources, certain of said sounds being represented in the record by corresponding frequencies and other sounds 110 being represented by frequencies higher than the original sounds.

In witness whereof, I hereunto subscribe my name this 28th day of October, 1929.
